UNITED STATES PATENT OFFICE.

CHARLES P. WOOD, OF SYRACUSE, NEW YORK.

DESIGN FOR A TOY CART.

57,067.

Specification for Design.

Patented Feb. 1, 1921.

Application filed August 27, 1920. Serial No. 406,488. Term of patent 14 years.

To all whom it may concern:

Be it known that I, CHARLES P. Wood, a citizen of the United States, residing in the city of Syracuse, in the county of Onondaga and State of New York, have invented a new, original, and ornamental Design for a Toy Cart, of which the following is a specification, reference being had to the accompanying drawing, forming part thereof.

The drawing is a perspective view of a toy cart showing my new design.

What I claim is:

The ornamental design for a toy cart as shown.

CHARLES P. WOOD.
